W. T. BARRATT.
SINKER WHEEL FOR KNITTING MACHINES.
APPLICATION FILED NOV. 12, 1921.

1,435,196.

Patented Nov. 14, 1922.

FIG. I.

FIG. 2.

Fig. 3.

Inventor:

William J. Barratt,
By his attorney,
Parker S. Gooding.

UNITED STATES PATENT OFFICE.

WILLIAM T. BARRATT, OF BENNINGTON, VERMONT, ASSIGNOR TO CHARLES S. KEHOE,
ANNIE COOPER, AND ALEXANDER J. COOPER, EXECUTORS OF CHARLES COOPER,
DECEASED.

SINKER WHEEL FOR KNITTING MACHINES.

Application filed November 12, 1921. Serial No. 514,544.

To all whom it may concern:

Be it known that I, WILLIAM T. BARRATT, a citizen of the United States, residing at Bennington, in the county of Bennington 5 and State of Vermont, have invented new and useful Improvements in Sinker Wheels for Knitting Machines, of which the following is a specification.

This invention relates to improvements in 10 circular knitting machines, and particularly to that portion of said knitting machines known as the sinker wheel.

The object of the invention is to provide 15 a sinker wheel which can be rotated by the needles of the cylinder and which also has embodied therein a gear so positioned and constructed that it will engage the needles of a knitting machine cylinder at a point beyond the cylinder adjacent to the hooked 20 end of the needles and support said needles against any strain that may be brought thereon laterally thereof, or in a direction tangential to the needle cylinder.

The invention consists primarily in providing 25 a sinker wheel with a gear adapted to be positioned to support the needles as hereinbefore set forth.

The invention further consists in providing 30 a sinker wheel having two gears fast thereto, one of said gears being positioned to support the needles as hereinbefore set forth, the other of said gears being adapted to engage the needles where they contact with the needle cylinder and whereby rotary motion may be imparted to said sinker 35 wheel.

The invention further consists in the combination and arrangement of parts set forth 40 in the following specification and particularly pointed out in the claims thereof.

In the embodiment of my invention hereinafter described and illustrated in the drawings I have illustrated my improved sinker wheel in connection with a circular 45 rib knitting machine of the type illustrated and described in Patent Number 864,354 issued to me on August 27, 1907, "sinker-wheel for circular-knitting machines" and to this patent reference may be had for details of construction not specifically set forth in the following specification.

Referring to the drawings:

Figure 1 is a sectional elevation of a portion of a circular rib knitting machine show-

ing my improved sinker wheel in connection 55 therewith.

Fig. 2 is a detail plan of the sinker wheel.

Fig. 3 is a side elevation of the sinker wheel showing a needle in connection therewith.

Like numerals refer to like parts throughout the several views of the drawings.

In the drawings, 10 is the bed plate upon which is rotatably supported the lower needle cylinder 11. 12 is the cap plate upon 65 which is rotatably supported an upper cylinder 13. The upper cylinder 13 is rotated by means of a gear 14 fast to the cylinder 13, the lower cylinder 11 being rotated in a similar manner by a gear not shown in the 70 drawings. The lower cylinder is provided with grooves or tricks 15 in its periphery in which the jacks 16 and their needles 17 are adapted to slide, said jacks and needles being moved longitudinally of the tricks 15 75 by the rotation of the cylinders coaxing with the needle cams 18 which are supported upon brackets 19 fast to the bed plate 10. The upper needles 20 are adapted to slide in tricks or grooves 21 formed in the periphery 80 of the upper cylinder 13. The upper needles 20 are connected to jacks 22 and are moved longitudinally of the tricks 21 by cams 23 fast to brackets 24, said brackets being fastened to the cap plate 12. The rotation of 85 the cylinders and the operation of the spring needles 17 and 20 is well known to those skilled in this art.

The sinker wheel 25 has a series of grooves 90 26 in the upper face thereof, said grooves radiating from a common center and in these grooves or tricks are located sinkers 27, each of said sinkers being provided with a lug 27' which projects into a groove 56 formed in the under face of the cam 30. The cam 30 95 has a hub 31 projecting upwardly therefrom which has a flush set screw 32 in screw-threaded engagement therewith adapted to bear against the shaft or stud 33 which is rigidly clamped at its lower end to a bracket 100 34 by means of a nut 35. The stud 33 is provided with a flange 36 which bears against the upper face of the bracket arm 34 and that portion of the stud between the flange 36 and the nut 35 projects through a slot 37 105 in the bracket 34 and is flattened off at 38 to prevent the rotation of said stud relatively to said bracket. The bracket 34 has a cylin-

drical stem 39 fast thereto or integral therewith which projects into a base 40 to which it is secured by set screws 41. It will be understood that the cam 30 is fastened to the stud 33 by the set screw 32 and said cam is further securely fastened to said stud in order to prevent rotation thereon by a collar 42 which is fastened to the stud 33 by set screws 43 and is locked to the cam 30 by a pin 44 which is fast to the collar 42 and projects downwardly therefrom into the hub 31 of said cam 30. The yarn 59 is guided to the sinkers 27 by yarn guides 60 and 61. The yarn guide 61 is fastened to the cap 15 plate 12 and the yarn guide 60 is fastened to a bracket 62 which, in turn, is fastened to the cam bracket 34. The gear 29 meshes into the needles 17 of the lower cylinder and projects into an annular groove 63 provided 20 in the periphery of the lower cylinder 11. Said gear is fastened to a hub 64 projecting downwardly from the sinker wheel 25 by a set screw 65. The hub 64 of the sinker wheel 25 has a bracket or arm 66 fast thereto and 25 forming, in effect, a portion thereof into which is screwed an adjusting screw 67 which rotatably engages a swivel bearing 68. The swivel bearing 68 consists of a screw 69 which engages the hub of the gear 30 14, the upper end of said screw being forked 35 to receive the shank of the screw 67 between the head 70 thereof and a flange formed thereon. The sinker wheel, in addition to the gear 29 which is adjustably fastened 40 thereto, as hereinbefore described has fast thereto or preferably integral therewith a gear 72, the teeth of which and the spaces therebetween are in alignment with the teeth and spaces of the gear 29 and the teeth of 45 said gear 72 engage the needles 17 adjacent their hooked ends and engage that portion of said needles which at the time of said engagement are projected above the needle cylinder 11. Thus the projecting ends of 50 the needles are supported against lateral distortion, bending or breaking by the teeth of the gear 72. The upper face of the gear 72 is flush with the lower edges of the sinkers so that the needles are supported by the gear 72 at the lower edges of the sinkers.

The general operation of the mechanism hereinbefore described is the same as in that of said patent, the particular advantage secured by the sinker wheel of this invention 55 being that the needles where they are unsupported beyond the needle cylinder as in said patent are firmly supported with the desirable results hereinbefore set forth by the gear 72.

60 It will be understood that the gear 72 as

illustrated in the drawings is integral with the sinker wheel and this is the preferred construction, but it is evident that without departing from the spirit of my invention, said gear 72 may be made in a separate piece 65 from the sinker wheel and fastened thereto by any suitable means. In either case it will be evident that the gear 72 is fast to the sinker wheel, either by being fastened thereto by screws, or other convenient mechanical devices, or by being cast in one piece therewith, and in the following claims the words "fast thereto" are to be interpreted 70 in this sense.

I claim:

1. A sinker wheel for a circular knitting machine and a pair of gears fast thereto, one of said gears being adapted to engage that portion of the needles of said knitting machine which contacts with the needle cylinder 80 while the other of said gears engages that portion of said needles adjacent their hooked ends and which is out of contact with said needle cylinder.

2. A rotary sinker wheel for circular knitting machines, a plurality of sinkers adapted to slide in grooves provided in said sinker wheel and a gear on said sinker wheel adjacent the bottom of said grooves and adapted to engage that portion of the needles of said 90 knitting machine adjacent their hooked ends and which is out of contact with the needle cylinder.

3. In a circular knitting machine a needle cylinder, a set of needles adapted to slide in grooves provided in the periphery of said cylinder, a sinker wheel, and a gear fast to said sinker wheel and adapted to engage that portion of said needles adjacent their hooked ends while out of contact with said needle 100 cylinder.

4. In a circular knitting machine a needle cylinder, a set of needles adapted to slide in grooves provided in the periphery of said cylinder, a sinker wheel, a gear fast thereto 105 and meshing into said needles at that portion thereof which contacts with said needle cylinder and another gear fast to said sinker wheel and adapted to engage that portion of said needles adjacent their hooked ends 110 while out of contact with said needle cylinder.

In testimony whereof I have hereunto set my hand in presence of two subscribing witnesses.

WILLIAM T. BARRATT.

Witnesses:

FRANK HURLEY,
ALFRED LA FRANCHISE.
